DESIGN FOR A DRESS

Abraham H. Bleich, Newton, Mass.

Application January 24, 1941, Serial No. 98,371

Term of patent 7 years

To all whom it may concern:

Be it known that I, Abraham H. Bleich, a citizen of the United States and resident of Newton, in the county of Middlesex, State of Massachusetts, have invented a new, original, and ornamental Design for a Dress, of which the following is a specification, reference being had to the accompanying drawing, forming part thereof.

Fig. 1 is a front elevation of a dress showing my new design; and

Fig. 2 is a rear elevation thereof.

I claim:

The ornamental design for a dress, as shown.

ABRAHAM H. BLEICH.
